Des. 221,275
Patented July 27, 1971

221,275

DISPENSING CONTAINER FOR LIQUIDS

Peter B. Hebblethwaite, Ashford, England, assignor to Graviner (Colnbrook) Limited, London, England

Filed Apr. 15, 1970, Ser. No. 22,433

Term of patent 14 years

Int. Cl. D9—01

U.S. Cl. D9—9

FIG. 1

FIG. 2.

FIG. 3.

FIG. 4.

FIG. 5.

FIG. 1 is a perspective view of a dispensing container for liquids showing my new design;

FIG. 2 is a front elevational view;

FIG. 3 is a side elevational view;

FIG. 4 is a bottom plan view; and

FIG. 5 is a top plan view thereof.

I claim:

The ornamental design for a dispensing container for liquids, as shown.
